UNITED STATES PATENT OFFICE.

WILLIAM RICHTER, OF NEW YORK, N. Y.

HEATER.

SPECIFICATION forming part of Letters Patent No. 782,699, dated February 14, 1905.

Application filed June 30, 1904. Serial No. 214,763.

To all whom it may concern:

Be it known that I, WILLIAM RICHTER, a citizen of the United States, and a resident of the city of New York, borough of Manhattan, in the county and State of New York, have invented a new and Improved Heater, of which the following is a full, clear, and exact description.

The invention relates to stoves such as are used for heating purposes and employing gas, vapors, or other oil fuel; and its object is to provide a new and improved heater which is simple and durable in construction and arranged to provide a large heating-surface in a comparatively small space and to produce a proper circulation of the air and thorough heating thereof.

The invention consists of novel features and parts and combinations of the same, as will be more fully described hereinafter, and then pointed out in the claims.

A practical embodiment of the invention is represented in the accompanying drawings, forming a part of this specification, in which similar characters of reference indicate corresponding parts in all the views.

Figure 1 is a side elevation of the improvement, parts being in section. Fig. 2 is an enlarged sectional side elevation of part of the same. Fig. 3 is a plan view of the same. Fig. 4 is a sectional plan view of one of the tubes and its bottom supporting-plate, and Fig. 5 is a perspective view of one of the members of a heating-cell.

In the upper portion of each of the tubes A of a heating-stove using gas or oil as a fuel is suspended a heating-cell B, formed of a plurality of members C, located one above the other, each member being formed of a sheet-metal plate C', having depending side flanges C² and end flanges C³, of which the side flanges C² are bent inwardly and the side flanges of one plate rest on the upper surface of the next plate below, as will be readily understood by reference to Fig. 2. The plates C' of the several members C are strung on a rod D, fastened at its upper end by nuts D' on a cross-bar E, resting on a top plate F, seated on the upper ends of the tubes A and connected by

rods F' with a bottom plate F², bolted or otherwise fastened to the base G of the heater. A burner H for the lower end of each tube A is secured on a suitable gas-supply pipe H', so that when the gas issuing from the burner is ignited the air in the tube is heated and rises and finally comes in contact with the cell B, which serves to retard the rising of the air and causes a circulation of the air between the several members to insure a high heating of the air before the same escapes at the upper ends of the tubes A.

By reference to Fig. 3 it will be seen that the tubes A are preferably oval in cross-section and the plates C' are approximately rectangular in shape, so as to fit the tubes sufficiently close to form passage-ways I and I', of which the passage-ways I are between the side flanges C² of the plates and the interior face of the corresponding tube A, while the passage-ways I' are between the end flanges C³ and the inner face of the tube A. By inclining the side flanges C² inwardly and downwardly and forming each side flange with a cut-out portion C⁴ it is evident that the portion of the air rising in one of the side passage-ways I strikes the flanges C² and passes through the cut-out portion C⁴ between two succeeding plates C', and air rising in the passage-ways I' can also pass between successive plates, as the flanges C³ are considerably shorter than the side flanges C², and each end flange C³ is in addition provided with a cut-out portion C⁵, extending from the bottom edge of the flange to the under side of the plate C'.

The cut-out portion C⁴ of each side flange C² extends from the bottom edge of the flange to within a distance of the under side of a plate C', so as to somewhat confine or hold the air under a plate C' to cause the air to pass out through an opening C⁶ into an end passage I'. The portions C⁷ of the lower edges of the side flanges C² are beveled to form with the top face of the plate C' of the next member C below an opening leading to the cut-out portion C⁴ to insure the gradual circulation of the air toward the cut-out portion C⁴.

From the foregoing it will be seen that by

the arrangement described the heat rising in a tube A is retarded by the members C of the heating-cell, and the heat is also expanded between the plates C' of adjacent members, thus causing a perfect circulation of the air between the members to insure a thorough heating of the members.

By making the depending end flanges C³ of each member C short and terminating the same a distance above the plate C' of the next member C below sufficient openings are provided for the air to circulate freely between adjacent members and in a transverse direction relative to the tubes A.

15 The side flanges C³ of the lowermost member C (see Fig. 1) are curved outwardly to abut against the inner surface of the tube A to hold the entire cell against lateral movement, thereby preventing all rattling and jar-

20 ring of the cell in the tube A.

Having thus described my invention, I claim as new and desire to secure by Letters Patent—

1. In a heater for burning gas or oil a heating-cell consisting of a plurality of superimposed members, each having a plate of an approximately rectangular shape, side flanges extending integrally from the said plate and butting on the plate of the next member to space the members apart, and end flanges extending from the plate and terminating a distance from the plate of the next member.

2. In a heater for burning gas or oil a heating-cell consisting of a plurality of superimposed members, each having a plate of an approximately rectangular shape, side flanges extending integrally from the said plate and butting on the plate of the next member to space the members apart, the side flanges being inclined inwardly, and end flanges extending from the plate and terminating a distance from the plate of the next member.

3. In a heater for burning gas or oil a heating-cell consisting of a plurality of superimposed members, each having a plate of an approximately rectangular shape, side flanges extending integrally from the said plate and butting on the plate of the next member, the said flanges having cut-out portions, extending from the bottom edge to within a distance of the plate, and end flanges extending from the plate and terminating a distance from the plate of the next member, the end flanges having cut-out portions.

4. In a heater for burning gas or oil a heating-cell consisting of a central suspending-rod and a plurality of superimposed members held on the said rod, each member having a plate of an approximately rectangular shape, side flanges extending integrally from the said plate and butting on the plate of the next adjacent member, the said side flanges holding the members spaced apart, and end flanges extending from the plate and terminating a

distance from the plate of the next adjacent member.

65

5. In a heater for burning gas or oil, a tube, and a heating-cell suspended in the upper portion of the tube and formed of a plurality of members, each consisting of a plate having depending side flanges and depending end flanges, the side flanges of a plate resting on the top of the next plate below to space the members apart.

6. In a heater for burning gas or oil, a tube, and a heating-cell suspended in the upper portion of the tube and formed of a plurality of members, each consisting of a plate having depending side flanges and depending end flanges, the side flanges of a plate resting on the top of the next plate below to space the members apart and the end flanges terminating a distance from the said next plate.

7. In a heater for burning gas or oil, a tube, and a heating-cell suspended in the upper portion of the tube and formed of a plurality of members, each consisting of a plate having depending side flanges and depending end flanges, the side flanges of a plate resting on the top of the next plate below to space the members apart and the end flanges terminating a distance from the said next plate, and both sets of flanges having cut-out portions for the passage of air.

8. In a heater for burning gas or oil, a tube, and a heating-cell suspended therein and formed of a plurality of members located one above the other and spaced from each other, the members forming with the tube vertical passage-ways for the heat the passage-ways being spaced apart and the said members having flanges provided with cut-out portions for the air to pass laterally into the said passage-ways.

9. In a heater for burning gas or oil, a tube, and a heating-cell suspended therein, and formed of a plurality of members located one above the other and spaced from each other, the members forming with the tube vertical passage-ways for the heat and the lowermost member having outwardly-bent flanges abutting against the inner wall of the tube.

10. In a heater for burning gas or oil, a tube, and a heating-cell suspended therein and formed of a plurality of members located one above the other and spaced from each other, the members forming with the tube vertical passage-ways for the heat, each member consisting of a plate having depending end flanges and inwardly-bent side flanges, of which the side flanges of one plate rest on the next plate below.

11. In a heater for burning gas or oil, a tube, and a heating-cell suspended therein and formed of a plurality of members located one above the other and spaced from each other, the members forming with the tube vertical

passage-ways for the heat, each member consisting of a plate having depending end flanges and inwardly-bent side flanges, of which the side flanges of one plate rest on the next plate 5 below, and the side flanges of the lowermost plate are bent outward to abut against the inner face of the tube.

In testimony whereof I have signed my name to this specification in the presence of two subscribing witnesses.
